UNITED STATES PATENT OFFICE.

BERT GILBERT GARTIN, OF FELLOWS, CALIFORNIA.

APPARATUS FOR CONTROLLING THE FLOW OF LUBRICATING-OIL IN MOTORS OF MOTOR-VEHICLES.

1,302,535.

Specification of Letters Patent.

Patented May 6, 1919.

Application filed May 23, 1918. Serial No. 236,286.

To all whom it may concern:

Be it known that I, BERT G. GARTIN, a citizen of the United States of America, residing at Fellows, in the county of Kern and State of California, have invented certain new and useful Improvements in Apparatus for Controlling the Flow of Lubricating Oil in Motors of Motor-Vehicles, of which the following is a specification, reference being had therein to the accompanying drawings.

This invention relates to an apparatus for controlling the flow of lubricating oil in a motor of motor vehicles, and has for its principal object the provision of simple and efficient means for supplying the motor throughout its length with sufficient lubricating oil whether the motor is on a level or on an incline, by reason of the motor vehicle either traveling along a horizontal or level road bed or ascending or descending a hill.

With these and other objects in view, this invention consists of certain novel combinations and arrangements of parts as will be hereinafter fully described and claimed.

In the drawings:

Figure 1 is a view in side elevation of a motor showing my apparatus applied thereto, while

Fig. 2 is a top plan view of the motor and apparatus shown in Fig. 1.

Fig. 3 is a view in side elevation of the controller reservoir or casing, with the front or face plate removed.

Fig. 4 is a horizontal sectional view of the controller casing taken on line 4—4, Fig. 3.

Fig. 5 is a vertical sectional view of the controller casing taken on line 5—5, Fig. 3.

Fig. 6 is a perspective view of the pendulum of the controller casing.

Fig. 7 is a detail view of the entrance or inlet pipe of the apparatus, while

Fig. 8 is a fragmentary view of the motor and the inlet pipe, showing the position of the funnel-shaped-end of the inlet pipe with relation to the fly wheel motor.

Fig. 9 is a fragmentary view of the motor showing the manner of attaching the controller casing by means of brackets to the motor casing.

Fig. 10 is a fragmentary, longitudinal sectional view of the valve pipes or tubes in the controller casing, while

Fig. 11 is a sectional view taken on line 11—11, Fig. 3.

Fig. 12 is a view of the controller casing,

showing another embodiment of the discharge pipe leading therefrom and being positioned in the ordinary inlet of a motor, through the means of which inlet lubricating oil is supplied to the engine.

60

Referring to the drawings by numerals 1 designates a controller casing which is provided with a front, detachable plate or cover 2, which cover or plate 2 is normally held in position by means of screws 3, which screws 65 enter the threaded sockets 4.

The casing 1 is attached by a primary bracket 5 and an auxiliary bracket 6 (Fig. 9) to the motor casing 7 through the medium of bolts 8 and 9; it will be seen that the ordinary bolts or connecting means 9 of a motor may be employed for securing the controller casing to the motor.

The controller casing 1 is provided with a threaded plug 10 that constitutes a closure means for the opening 11, which opening 11 is provided for draining the casing 1.

A wire mesh 12 divides the casing 1 near one side thereof into two compartments for the purpose hereinafter described. This wire mesh 12 extends entirely across the casing (see Fig. 4) and is retained by a suitable nut and bolt structure 13 at its bottom to the bottom of casing 1 and by a similar nut and bolt structure 14 whereby said mesh 12 is retained to the top of the casing 1.

An inlet supply pipe 15 extends into the casing 1 near its top, and this inlet pipe 15 extends outside of the motor casing and around to the front, as clearly seen in Figs. 1 and 2, and then the inlet pipe enters at 16 the motor casing 7 and the funnel-shaped-end 17 of the inlet pipe 15 is placed close to the fly wheel shown by dotted lines 18 in Figs. 1, 2, and 8.

Lubricating oil is "picked up" by the fly wheel as it revolves, as is well known, and it is discharged through the funnel-shaped-end 17 of the inlet pipe 15, thence the oil so discharged from the fly wheel 18 as it revolves, flows through the inlet pipe 15 and into the controller casing 1 in front of the straining wire-mesh 12.

The outlet or discharge pipe 19 extends through the opposite side of the casing 1, from that side through which the inner pipe 15 extends, and this outlet or discharge pipe 19 extends downwardly at 20, Fig. 9 and into the motor casing 7, as shown at 21.

The inner end of the discharge or outlet 20

pipe 19 is open, Fig. 4, and near the inner opened end of pipe 19 there are formed a plurality of outlet apertures or ports 22, which apertures or ports 22 are adapted to 5 register with apertures or ports 23 formed upon the sliding pipe or casing 24; the inner end of the discharge pipe 19 and the sliding pipe or casing 24 constitutes a sectional valve as will be more fully understood from 10 the following description.

A pendulum is pivotally mounted in the casing 1, and said pendulum comprises the body portion 25 having a weighted lower end 26; the body 25 is provided near its 15 upper end with a bolt receiving aperture 27 and near said aperture 27 is an elongated aperture 28. A bifurcated lug structure 29 is formed on the inner face of the top of the casing 1 (see Figs. 1 and 5) and the apertured end of the pendulum is positioned therein, and a bolt 30 extends through the apertured lug structure 29 and through the aperture 27 of the pendulum, holding the pendulum in the casing 1 in an operable position. 20 A bolt 31 extends through the inner end of the outer section or pipe 24 and bolt 31 is positioned in the elongated aperture 28 of the pendulum; the elongation of the aperture 28 allows the pendulum to swing 25 within casing 1 so that the outer section 24 of the valve may be adjusted longitudinally on the inner end of the discharge pipe 19. The inner end of the outer section or pipe 24 is slotted at 32, Fig. 4, to allow the 30 pendulum to swing therein, and the inner end of said pipe or section 24 is closed by 35 filler or plug 33, Fig. 4, so that oil is only allowed to pass from casing 1 into the discharge pipe 19 through the registering apertures 22 and 23 of the valve device.

In Fig. 12 I have shown the discharge or outlet pipe 19 extending through the side of the ordinary filler tube 34 of a motor vehicle, which tube 34 is used for supplying 40 lubricating oil to the motor; in this embodiment, instead of having the portion 20^a extending through the side of the motor casing, as clearly shown in Fig. 9, this portion 20^a extends down the supply tube 34, permitting 45 the oil or lubricant to pass from the container or controller casing 1 back into the motor as desired.

It will be understood that the crank shaft of a motor splashes the lubricant provided 50 the oil is so distributed throughout the length of the motor casing so as to permit the crank shafts in their traveling (in their lowest position) to come in contact with lubricating oil. In many motors this splashing or lubricating of the crank shaft and its 55 pistons is satisfactorily accomplished when the motor vehicle is on the level, but when the vehicle is ascending or descending a hill or grade the lubricating of the crank and 60 the pistons is not satisfactory, but by em-

ploying my improved lubricating apparatus the lubrication of the motor is automatically and satisfactorily accomplished whether the motor vehicle is on a level or on an incline. Now, to better understand the operation of 70 my apparatus, I cause the oil thrown off the fly wheel 18 to enter the inlet tube 15 at its funnel-shaped-end 17 at all times; normally the pendulum is in the position shown in Fig. 3 when the machine or motor is on 75 a level roadway, and the registering apertures or ports 22 and 23 are partly closed allowing of a small quantity of lubricant to pass out of the container casing 1 and be discharged at the forward end of the motor 80 casing, from which forward end the lubricant gradually flows to the rear end of the motor casing, to the large reservoir 35 in which the lower end of the fly wheel 18 is positioned, Fig. 1.

Upon descending a hill or incline, the lubricant runs freely from the large reservoir 35 to the forward end of the motor 85 thereby furnishing sufficient lubricant to lubricate the crank shaft and pistons; upon the machine being inclined downwardly at its forward end, the pendulum will be pitched or swung to the dotted position 36, Fig. 3, closing the apertures or ports so that no oil or lubricant is permitted to pass from the controller casing 1 into the discharge pipe 19, since the motor is securing enough oil from the reservoir 35 to satisfy the needs of the motor, by reason of the inclination or 90 inclined position of the machine. Now, upon ascending a hill, the tendency is for all of the oil or lubricant to run back into the reservoir 35 and leave the crank shaft, and to overcome this, the pendulum will swing 95 rearwardly to the position indicated by dotted lines 37, Fig. 3, opening the ports or apertures 22 and 23 to their fullest, allowing of oil or lubricant to pass freely into the pipe 19 and uniformly supply the entire 100 motor casing with the lubricant, which portion of the motor casing carrying the crank shaft in some motors would be substantially dry, but by using my apparatus a uniform distribution of the lubricant is permitted at all times irrespective as to 105 whether the motor is in a horizontal position or an inclined position.

The straining mesh 12 prevents any foreign substance coming from the engine casing in the oil discharged from pipe 15 110 into casing 1, from being returned to the engine casing through the pipe 19; from time to time plug 10 can be removed and the sediment or foreign substance removed from casing 1; only clean and strained oil or 115 lubricant is discharged through ports 22 and 23 into the discharge pipe 19.

In the appended claims I use the term "inlet pipe" and "outlet pipe" in a broad sense, since tubing or communicating means other 120

than a pipe may be used without departing from the scope of the present invention.

I reserve the right to make certain alterations and changes in carrying out my invention, from the referred embodiment hereinbefore described, as shall fairly fall within the scope of the appended claims.

What I claim is:

1. In an apparatus of the class described, the combination with a motor casing, a fly wheel in said motor casing, of a controller casing detachably mounted upon the side of said motor casing, an inlet pipe and an outlet pipe carried by said controller casing, both pipes extending into said motor casing, said inlet pipe having its inner end positioned near the fly wheel, and a pendulum controlled valve device in said controller casing and coöperating with the discharge pipe for controlling the supply of oil therethrough.

2. In an apparatus of the class described, the combination of a controller casing, an inlet and an outlet pipe communicating with said controller casing, a strainer mesh secured in said casing and dividing the same between said inlet and outlet pipes, and a valve device in said controller casing between said strainer mesh and said discharge pipe.

3. In an apparatus of the class described, the combination with a controller casing provided with inlet and outlet pipes, of a valve device in said controller casing, said valve device comprising the inner end of said outlet pipe, said outlet pipe being provided with apertures near its inner end, a sliding pipe or section provided with apertures mounted upon the inner end of said outlet pipe, a pendulum carried by said controller casing, and means connecting said

pendulum to said pipe or section on the inner end of said outlet pipe for moving the section and controlling the size of the passage constructed by the apertures on said outlet pipe and said section sliding thereon.

4. In an apparatus of the class described, the combination with a controller casing provided with inlet and outlet pipes, of a valve device in said controller casing comprising a weighted pendulum, a pipe pivotally connected to said pendulum and slidably mounted upon the inner end of said discharge pipe, and said discharge pipe and slidably mounted pipe of the pendulum both provided with apertures adapted to register for permitting a lubricant to flow through said apertures and into said discharge pipe.

5. In an apparatus of the class described, the combination of a controller casing provided with inlet and outlet pipes, said outlet pipe projecting a considerable distance into said casing, said outlet pipe being provided near its inner end with a plurality of apertures, a sliding pipe mounted upon the inner end of said outlet pipe, said sliding pipe being provided with apertures being adapted to register with the apertures of the outlet pipe, said sliding pipe being provided with a slotted end, a plug or closure means in said sliding pipe near its slotted end, a pendulum provided with a weighted lower end and with an elongated aperture near its upper end, fastening means extending through the slotted portion of said sliding pipe and through the elongated aperture of said pendulum, and means pivotally suspending said pendulum from the top of said casing.

In testimony whereof I hereunto affix my signature.

BERT GILBERT GARTIN.
